W. L. PIERCE.
HEMSTITCH ATTACHMENT FOR SEWING MACHINES.
APPLICATION FILED JAN. 9, 1919.

1,401,726.

Patented Dec. 27, 1921.

UNITED STATES PATENT OFFICE.

WILLIAM L. PIERCE, OF NEW YORK, N. Y.

HEMSTITCH ATTACHMENT FOR SEWING-MACHINES.

1,401,726.

Specification of Letters Patent. Patented Dec. 27, 1921.

Application filed January 9, 1919. Serial No. 270,277.

To all whom it may concern:

Be it known that I, WILLIAM L. PIERCE, a citizen of the United States, residing at New York, county and State of New York, have made a certain new and useful Invention in Hemstitch Attachment for Sewing-Machines, of which the following is a specification.

This invention relates to hem stitch attachment for sewing machines.

The object of the invention is to provide a hem stitch attachment which is simple in construction, efficient in operation, and economical of manufacture.

A further object of the invention is to provide an attachment of the class described which permits turning corners or sharp angles without losing a stitch.

A further object of the invention is to provide a device of the character described wherein the sides of the hem stitched portion is provided with a binding cord for decorative or strengthening purposes.

A further object of the invention is to provide means which will insure the binding cord being stitched to the material no matter what direction or through what angles and curves the material is fed to the machine.

Further objects of the invention will appear more fully hereinafter.

The invention consists substantially in the construction, combination, location and relative arrangement of parts, all as will be more fully hereinafter set forth as shown by the accompanying drawings, and finally pointed out in the appended claims.

Referring to the drawings:—

Figure 1 is a view in side elevation of a presser foot including the hem stitch arrangement embodying my invention.

Fig. 2 is a sectional view taken on the line 2, 2, Fig. 1, looking in the direction of the arrows.

Fig. 3 is a view in side elevation of one member of the presser foot to which is secured the attachment embodying my invention, and is a sectional view taken on the line 3, 3, Fig. 4, looking in the direction of the arrows.

Fig. 4 is a front view of the presser foot.

Fig. 5 is a sectional view taken on the line 5, 5, Fig. 3, and looking in the direction of the arrows.

Fig. 6 is a view in perspective, slightly enlarged, of the lower presser foot shown in Fig. 3.

Fig. 7 is a similar view of a slightly modified construction embodying my invention.

The same part is designated by the same reference character wherever the same occurs throughout the several views.

This present invention is directed particularly to hem stitching attachments for sewing machines wherein a cord is fastened under the stitch. In further explanation, it is directed to machines where a plunger is operated at intervals to punch a hole into the cloth or material which is being operated upon, and wherein a border comprising a cord of suitable texture or material and color borders the hole formed by the punch or plunger on each side thereof and is secured to the material by the stitching action of the threaded needle. Great difficulty has been encountered heretofore in attachments of this nature due to the fact that while the operation is satisfactory and the work is efficient and neat as long as a straight line of work is being effected, as soon as it is necessary to turn a corner or a curve in the material the cords do not come under the action of the stitching needles, and as is frequently the case, the cord of one side jumps to the other side and both cords are either unstitched entirely or are stitched together.

It is among the special purposes of my present invention to provide means for overcoming this defect and for insuring at all times no matter at what angle the material is fed to the machine and no matter what angles or curves it is required to turn the cords remain in their proper position and each stitch is perfectly secured.

Further, in the type of devices of this nature heretofore employed when a defect has occurred it is necessary to cut the cord and thread and to rethread the cord through its guideways which heretofore have been horizontal, that is, parallel to the plane of the goods being operated upon. Inasmuch as the space between the presser foot and the goods operated upon is exceedingly small, it is quite difficult to effect the threading of the cord through its guideways and requires time, patience and labor. It is among the further purposes of my present invention to prevent these difficulties and to provide means whereby the cord may be easily and readily threaded in the initial operation of the machine, it being understood that rethreading, due to cutting of the cord on account of imperfect stitching seldom, if ever,

occurs with the improved device of my invention.

The presser foot is shown generally in Fig. 1, and consists of two standards, 1 and 5 2, adapted to be suitably carried by the machine to which the same is attached in the usual and well known manner, for example, by means of set screws or the like. Each of the standards 1 and 2 has pivoted to the 10 lower end thereof for limited pivotal movement relative thereto presser feet 3 and 4 respectively. The front end of said presser feet is upturned as at 5 to prevent snagging or catching the goods or material to be operated upon which passes thereunder. The 15 two standards 1 and 2 are secured together by means of the rivet or pin 6 for pivotal movement relative to each other about said pin or rivet 6 but for simultaneous movement in vertical direction. The opposed surfaces of the feet 3 and 4 have at their rearward ends projections 7 which extend toward each other and form a plate extending into the space between the respective 20 feet 3 and 4 to prevent the goods being operated upon from rising or buckling under the presser feet and to keep same smooth after having been sewed. The forward ends of the plates 7 are curved as indicated 25 at 8. The forward end of the presser foot 4 is provided with a plate 9 which extends substantially across the intervening space between the opposed inner surfaces of the feet 3 and 4, the plate 9 being 30 for the purpose of keeping the goods flat after it is being led to the position where the respective needles operate upon it. The rear end of the plate 9 is curved and together with the curved surface 8 of the plates 7 35 forms a pocket between the presser feet, and between the respective plates 7 and 9 in which the sewing operation is effected. Secured to the inner surface of the presser foot 3 is an angle plate 10, the end of which 11, 40 45 is disposed at right angles relative to the surface of the foot 3 and extends into the pocket formed by the plates 9 and 7. The angle plate 11 is provided with two openings 12 extending therethrough and through 50 which the cord as above explained is led. The respective needles as is usual with hem stitching machines comprise a single cutting plunger and a pair of stitching needles, one for each side of the hem stitch. The plunger 55 operates before the angle plate 11 and is indicated in Fig. 2 by 13. The respective needles operate by the angle plate 11 indicated in Fig. 2 by 14. It will be understood as is usual in the art the stitching needles 14 60 operate toward and away from each other, that is, on one operation of the stitching needles the needles are fairly close together and on the next operation of the needles, that is, the next time it passes through the 65 goods the needles are operated away from

each other, thus securing a stitch over a definitely prescribed distance. The effect will be more apparent by reference to Fig. 5. The plunger needle 13 being positioned in advance of the angle plate 11 cuts the hole 70 into the goods. The cord indicated by dotted lines passing through the holes 12 in the angle plate 11, which holes extend in a plane parallel to the plane of the goods being operated upon, is fed to the action of the 75 needles 14, the needles 14 on one stroke being on the inside of the cord as indicated at 14^a, and on the next stroke being on the outside of the cord as indicated at 14^b. Thus it will be seen that the cord is stitched as a 80 border to the holes cut in the goods by the plunger 13 and the hem stitch completed. It will be seen by reference to Fig. 3 that the angle plate 11 extends substantially the same distance as the plates 7 and 9 and in effect 85 also forms a plate between the two points of operation for holding the goods treated in a flat position. The advantages of this construction are apparent. In the first place by leading the cord directly and in close 90 proximity to the point to which it is treated I insure even in the sharpest turns the action of the stitching needles 14 on the respective cords passing through the guides 12 of the angle plate 11. Furthermore, means are 95 provided for at all times keeping the material, and particularly at the point where the same is operated upon, in a perfectly flat condition. Furthermore, by providing the guide holes 12 in the angle plate 11 in a 100 plane parallel to the plane of the goods to be operated upon I afford simple means for threading the cord which makes possible the threading thereof with little or no trouble or lapse of time.

Many modifications will occur to those skilled in the art without departing from the broad spirit and scope of my invention as defined in the claims, and I therefore do not desire to be limited to the particular form 110 of my invention shown and described, for example, and referring to Fig. 7, the presser foot 3 may be equipped with a turn plate 20 suitably secured thereto for turning the goods which is fed to the machine to form a 115 smooth edge for the material which is being hemstitched. By further turning the edge 21 of the member 20 the material can be turned twice.

Having now set forth the objects and nature of my invention, and having shown and described a structure embodying the principles thereof, what I claim as new and useful and of my own invention, and desire to secure by Letters Patent is,—

1. In a cord border hemstitching attachment for sewing machines, the combination with a cutting plunger and stitching needles for stitching a cord border on opposite sides of the hole cut by said cutting plunger, of a 130

cord guide positioned between said cutting plunger and said stitching needles.

2. In a cord border hemstitching attachment for sewing machines, the combination 5 with a cutting plunger and stitching needles for stitching a cord border on opposite sides of the hole cut by said cutting plunger, of presser feet for holding the material operated upon in a flat position, of a cord guide 10 carried by one of said presser feet and positioned between said cutting plunger and said stitching needles.

3. In a cord border hemstitching attachment for sewing machines, the combination 15 with a cutting plunger and stitching needles for stitching a cord border on opposite sides of the hole cut by said cutting plunger, of a cord guide positioned between said cutting plunger and said stitching needles, and provided 20 with threading or guide holes extending in a plane parallel to the plane of the material operated upon.

4. In a cord border hemstitching attachment for sewing machines, the combination 25 with a cutting plunger and stitching needles for stitching a cord border on opposite sides of the hole cut by said cutting plunger, of presser feet for holding the material operated upon in a flat position, of a cord guide 30 carried by one of said presser feet and positioned between said cutting plunger and said stitching needles, and provided with threading or guide holes extending in a plane parallel to the plane of the material operated 35 upon.

5. The combination with a pair of independently movable spaced presser feet, of means carried thereby for forming an inclosure therebetween, intermediate the ends 40 thereof, a guide plate carried by one of said feet and a cord guide member carried by the other of said feet, and extending across the inclosure and cord guide member being provided with threading or guide holes extending 45 in a plane parallel to the plane of said presser feet.

6. The combination with a pair of pivotally mounted and spaced presser feet, of a smoothing member carried by one of said 50 feet, and a cord guide carried by the other of said feet, said guide member having

threading holes therethrough in a plane parallel to the plane of said feet.

7. In a cord border hemstitching attachment for sewing machines, the combination 55 with a cutting plunger and stitching needles for stitching a cord border on opposite sides of the hole cut by said cutting plunger, of presser feet for holding the material operated upon in a flat position, of a cord guide 60 carried by one of said presser feet and positioned between said cutting plunger and said stitching needles, and with the bottom surface thereof flush with the bottom surface of said presser feet.

8. The combination with a pair of spaced standards and a pair of presser feet pivoted thereon, of means carried by said feet for forming an inclosure therebetween, intermediate the ends thereof, a cord guide member carried by one of said feet, and extending across the inclosure and provided with threading or guide holes extending in a plane parallel to the plane of said presser feet and with the bottom surface thereof flush with 70 the bottom surface of said presser feet.

9. The combination with a pair of spaced presser feet, of a cord guide carried by one of said presser feet and extending transversely across the space between said feet 75 and provided with threading or guide holes extending in a plane parallel to the plane of said feet and with the bottom surface thereof flush with the bottom surface of said presser feet and a smoothing plate carried by 80 the other of said feet.

10. In a hem stitching mechanism the combination of a pair of spaced standards carrying a pair of pivotally mounted spaced presser feet, of a smoothing plate carried 85 by one of said presser feet, and a cord guide carried by the other of said feet, said smoothing plate and said cord guide extending transversely across a space between said feet, and operating independently to respectively 90 smooth the goods and to feed the cords to the stitching mechanism.

In testimony whereof I have hereunto set my hand on this second day of January, A. D., 1919.

WILLIAM L. PIERCE.
